(57) **CLAIM**

The ornamental design for a grocery bag holder device, as shown.

DESCRIPTION

FIG. 1 is a front plan view of a grocery bag holder device showing my new design;

FIG. 2 is a top plan view thereof;

FIG. 3 is a bottom plan view thereof;

FIG. 4 is a right plan view thereof;

FIG. 5 is a left plan view thereof;

FIG. 6 is a rear plan view thereof; and,

FIG. 7 is a front perspective view thereof.

The broken-line disclosure of a portion of a bag in the views is for illustrative purposes only and forms no part of the claimed design.
